(57) **CLAIM**

The ornamental design for a hair curling apparatus, as shown and described.

DESCRIPTION

Figure 1.1 is a top perspective view of a hair curling apparatus showing our new design;

Figure 1.2 is a bottom view thereof;

Figure 1.3 is a front view thereof;

Figure 1.4 is a left side view thereof;

Figure 1.5 is a rear view thereof;

Figure 1.6 is a top view thereof;

Figure 1.7 is a top rear perspective view thereof; and

Figure 1.8 is a right side view thereof.

In the drawings the portions of the article shown in broken lines do not form any part of the claimed design.

1 Claim, 8 Drawing Sheets
